UNITED STATES PATENT OFFICE

LUCIEN L. HAAS, OF BUFFALO, NEW YORK, ASSIGNOR TO BUFFALO PRESSED STEEL CO., OF BUFFALO, NEW YORK

MUFFLER WITH RELIEF VALVE

Application filed September 1, 1928. Serial No. 303,475.

This invention relates to mufflers or silencers for use in connection with internal combustion engines and more particularly to mufflers or silencers having cut-out valves for by-passing gases to the discharge of the muffler and thus reducing the back pressure caused by the muffler.

The objects of this invention are to provide a muffler provided with a plurality of sets or series of muffling chambers arranged in succession and having a by-pass controlled by a valve by means of which one or more series of chambers can be by-passed by the gases; also to provide a muffler of this kind with a chamber which forms a part of a by-pass when the cut-out valve is open and which acts as a buffer or cushioning chamber to increase the muffling effect of the muffler or silencer when the cut-out valve is closed; also to improve the construction of mufflers or silencers in other respects hereinafter specified.

In the accompanying drawings:

Figs. 1 and 2 are fragmentary sectional views of a muffler embodying this invention, Fig. 1 showing the inlet portion of the muffler and Fig. 2 showing the exhaust portion of the muffler.

Figs. 3, 4 and 5 are transverse sectional elevations respectively, on lines 3-3, 4-4 and 5-5 of Fig. 2.

Fig. 6 is a fragmentary sectional view on line 6-6 of Fig. 2.

My invention may be employed in connection with a muffler of any desired form or construction in which a plurality of muffling chambers are provided, and the particular muffler shown in the drawings is merely illustrated to show one embodiment of my invention, and it will be obvious that mufflers of other constructions may be used in connection with my invention if desired.

The muffler may be provided with an external shell A of any suitable or desired construction, that shown being made of three layers of material.

The shell, however, may be made of a single layer if desired. The shell is provided at the inlet end thereof with a head 10 having a central opening through which the in-

let pipe 11 extends, the pipe being secured to the head 10. A second head 12 is arranged at a distance from the inlet end of the muffler and is preferably formed with a series of shoulders, the outer one of which is secured to the inner face of the outer shell A of the muffler. Another head or baffle 14 is arranged adjacent to the opposite end of the muffler, (see Fig. 2) and the two heads or baffles are formed to support the opposite ends of a series of tubular members or shells B and C, the shell C engaging shouldered portions 17 and 18 respectively of the heads 12 and 14 and the shell B being supported on shoulders 20 and 21 respectively of the heads or baffles 12 and 14. The inner shell C is provided intermediate of the ends thereof with a transverse partition 24 which separates this shell into two chambers arranged lengthwise of the shell. An annular head 25 is arranged between the shells or tubes B and C and divides the space between these shells into two chambers.

In the particular construction shown the inner tube C is of substantially circular cross section and the tube B is of the elongated or elliptical cross section. The head 14 is arranged at a distance from the discharge end of the muffler and forms with an end wall or head 26, a chamber 27, the head 26 being provided with an exhaust or discharge tube or pipe 28. Through the chamber 27 extends a tube 30 which in the particular construction shown is bent or inclined and which connects the central portion of the head 14 with a side of a transverse partition wall 31 arranged at a slight distance from the discharge end of the muffler. The partition wall 31 is also provided with a discharge passage formed by a relatively heavy short length of tubing 33 in which a cut-out valve 34 is arranged, the valve 34 in the particular construction shown being mounted on a pivot or post 35 pivoted in the tube 33 and extending at one end through the outer shell A of the muffler.

At its outer end the valve stem 35 is provided with an arm 36 having any suitable connection 37 at its outer end by means of which the valve may be turned into an open

or closed position. Any other type of valve may be provided in place of the valve shown.

The inlet end of the tube or shell C is provided adjacent to the partition 24 with a series of holes or discharge openings 40 through which gases entering this tube through the inlet pipe 11 of the muffler may discharge into the chamber or space between the tubes or shells B and C. The shell B is provided adjacent to the head or baffle 12 with a series of discharge openings or holes 41 through which gases may enter into the chamber or space between the tubes or shells B and A of the muffler, the head 25 compelling the gases discharged from the openings 40 to pass lengthwise of the space between the tubes B and C, and thence through discharge openings 41 into the outer chamber or space 42. This space terminates in the head 14 which is provided with a series of openings 44 at the opposite sides thereof through which gases may pass from the outer chamber 42 into the chamber 27.

Consequently when the cut-out valve 34 is opened it will be noted that the gas from the outer chamber 42 to the muffler may discharge through the apertures 44 into the chamber 27 and thence through the tube 33 to the discharge pipe 28. Consequently the products of combustion will pass only through the first series or group of muffling chambers arranged between the inlet of the muffler and the partitions 24 and 25, and the chambers 42 and 27 to the discharge of the muffler. However, when the valve 34 is closed the chamber 27 has no discharge openings excepting openings 46 which are not of sufficient size to carry off all the gases entering the chamber 27 through the apertures 44, which are formed in the head 14 and the greater portion of the gases are then forced to pass from the chamber 42 through a series of openings 45 in the shell B.

Through these openings the gases enter the space between the shells B and C and between the partition 25 and the head 14. The openings 46 establish communication between the chamber 27 and the space between the tubes B and C, and some of the gases entering the equalizing chamber 27 may pass through the apertures 46 into the space between the shells B and C, which gases must reverse their direction of flow within the chamber 27 in order to pass through the apertures 46. The greater portion of the gases, however, pass through the apertures 45 in the shell B and do not enter the chamber 27, when the valve 34 is closed. In order to pass to the atmosphere from the space between the shells B and C and heads 25 and 14, the gases must pass through apertures 47 into the shell C and from the interior of this shell through the tube 30 into the discharge space between the transverse heads 31 and 26 at the discharge end of the muffler and thence through the

discharge pipe 28. This discharge space between the heads 31 and 26 serves mainly to conduct the gases, whether discharged through the pipe 30 or the valve pipe 33 to the discharge pipe 28 of the muffler. This space however also has a certain muffling effect by permitting the gases entering this space through either of the pipes 30 or 33 to expand before passing through the discharge pipe 28.

When the cut-out valve 36 is closed the gases are forced to pass from the chamber 42 through a second series of muffling chambers arranged one within the other and in this case the chamber 27 acts as a cushioning or equalizing chamber since gas entering into the outer chamber 42 of the muffler can, during the explosion of the engine, enter into the chamber 27 and compress the gases contained therein, and during the interval between explosions these compressed gases can discharge from the chamber 27 through the second series of muffling chambers and thence to the atmosphere. In this manner the chamber 27 serves to produce a more uniform flow of gas through the discharge chamber and consequently a better muffling or silencing is produced without increasing the back pressure of the gases in the muffler.

When the cut-out valve is opened, the gases introduced into the muffler are not discharged directly to the atmosphere as has heretofore commonly been done, but are passed through a series or group of muffling chambers before they are discharged to the atmosphere. Consequently the noise of the exhaust is greatly reduced without materially increasing the back pressure of the exhaust gases.

I claim as my invention:

1. A muffler having a series of muffling chambers through which all gases entering said muffler must pass, a second series of muffling chambers through which gases may pass after passing through said first series of chambers, a chamber located at the discharge end of said muffler and communicating with said two series of muffling chambers, and a valve in said chamber for discharging gases from said chamber without forcing the gases to pass through said second series of muffling chambers.

2. A muffler having a series of muffling chambers through which all gas entering said muffler must pass, a second series of muffling chambers through which gas may pass after passing through said first series of chambers, a combined by-pass and equalizing chamber which communicates with said first series of muffling chambers, and a valve in said by-pass and equalizing chamber which, when open, permits gases to discharge from said chamber to the atmosphere and which, when closed, causes gases to pass from said first series of muffling chambers to said second series and enables gases to be compressed

- in said equalizing chamber during the exhaust and to discharge therefrom to said second series of muffling chambers when pressure due to exhaust is reduced.
- 5 3. A muffler having a first series of muffling chambers arranged one within another, a second series of muffling chambers also arranged one within another and through which gases may pass after passing through said first series of chambers, and an equalizing chamber into which some of the gases may pass after having passed through said first series of muffling chambers and in which the gases may be alternately compressed and discharged to said second series of muffling chambers to equalize the flow of gas through said second series of chambers.
4. A muffler having a first series of muffling chambers arranged one within another, a second series of muffling chambers also arranged one within another and through which gases may pass after passing through said first series of chambers, an equalizing chamber into which some of the gases may pass after having passed through said first series of muffling chambers and in which the gases may be alternately compressed and discharged to said second series of muffling chambers to equalize the flow of gas through said second series of chambers, and a discharge passage leading from said second series of muffling chambers to the atmosphere and passing through said equalizing chamber.
- 35 5. A muffler having a first series of muffling chambers arranged one within another, a second series of muffling chambers also arranged one within another and through which gases may pass after passing through said first series of chambers, an equalizing chamber into which some of the gases may pass after having passed through said first series of muffling chambers and in which the gases may be alternately compressed and discharged to said second series of muffling chambers to equalize the flow of gas through said second series of chambers, and a valve in said equalizing chamber by means of which gas from said equalizing chamber may be discharged to the atmosphere.
6. A muffler having a first series of muffling chambers arranged one within another, a second series of muffling chambers also arranged one within another and through which gases may pass after passing through said first series of chambers, an equalizing chamber into which some of the gases may pass after having passed through first series of muffling chambers and in which the gases may be alternately compressed and discharged to said second series of muffling chambers to equalize the flow of gas through said second series of chambers, a discharge passage leading from said second series of muffling chambers to the atmosphere and passing through
- said equalizing chamber, and a valve in said equalizing chamber through which gases from the equalizing chamber may be discharged directly to the atmosphere without passing through said second series of muffling chambers.
7. A muffler including an outer, an intermediate and an inner shell, a transverse partition arranged in the inner shell and dividing the same into two chambers, a transverse partition arranged between the inner and intermediate shells and dividing the space between said shells into two chambers, means for admitting gases to one of the chambers of the inner shell, apertures through which gases are discharged from said chamber to one of the chambers between the intermediate and inner shells, apertures in said intermediate shell for discharging the gases to an outer chamber arranged between the intermediate and outer shell, an equalizing chamber which communicates with said outer chamber, a valve in said equalizing chamber for discharging gases from said equalizing chamber to the atmosphere when said valve is opened, and apertures for conducting gases from said outer chamber through the other chambers formed by said intermediate and outer shells when said valve is closed.
8. A muffler including a group of muffling chambers arranged one within another and through which gases pass from the inlet of the muffler, a second group of muffling chambers arranged one within another and beyond said first mentioned group of chambers, an outer chamber surrounding said two groups of muffling chambers and through which the gases pass from said first group to said second group, an equalizing chamber arranged beyond said second group of muffling chambers connecting with said outer chamber, a valve in said equalizing chamber for discharging gases from said equalizing chamber to the atmosphere without causing said gases to pass through said second group of muffling chambers, said valve when closed causing gases to flow from said outer chamber through said second group of muffling chambers and means for discharging gases from said second group of muffling chambers to the atmosphere.
9. A muffler having a series of muffling chambers through which all gases entering said muffler must pass, a second series of muffling chambers through which gases may pass after passing through said first series of chambers, a chamber located at the discharge end of said muffler and communicating with said two series of muffling chambers, a valve in said chamber for discharging gases from said chamber to the atmosphere without forcing the gases to pass through said second series of muffling chambers, and a passage extending from said second series of muffling chambers to the atmosphere and passing through

chambers through said chamber to the discharge end of said muffler.

10. A muffler having a series of muffling chambers through which all gases entering said muffler must pass, a second series of muffling chambers through which gases may pass after passing through said first series of chambers, a chamber communicating with said two series of chambers and which has gas receiving and discharging openings in the same side thereof to cause the direction of flow of the gases to be reversed, and a discharge valve in said chamber which may be opened to discharge gases from the muffler without causing them to flow through said second series of chambers.
